CLAIM

The ornamental design for a bottle with cap, as shown and described.

DESCRIPTION

FIG. 1 is a top, front, and left, perspective view of a bottle with cap showing our new design;

FIG. 2 is a bottom, rear, and right perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

Within the drawings, the even spaced dash-dash lines, and the areas within the dash-dash lines, show unclaimed portions of the bottle with cap and form no part of the claimed design. The surface shading lines are provided to indicate any contour or curvature of the surfaces.
